(57) **CLAIM**

The ornamental design for a display panel or screen or portion thereof with animated graphical user interface, as shown and described.

DESCRIPTION

FIG. 1 is a front view of a first embodiment of a display panel or screen or portion thereof with a first image of an animated graphical user interface showing our new design; FIG. 2 is a second image thereof; and FIG. 3 is a third image thereof.

FIG. 4 is a front view of a second embodiment of a display panel or screen or portion thereof with a first image of an animated graphical user interface showing our new design; FIG. 5 is a second image thereof; and, FIG. 6 is a third image thereof.

The broken lines shown in the drawings represent portions of the display panel or screen with a graphical user interface and form no part of the claimed design.

The appearance of the image transitions sequentially between FIGS. 1-3 and between FIGS. 4-6, respectively.

The process or period in which an image transitions to another forms no part of the claimed design.
